UNITED STATES PATENT OFFICE

PIROSKA ELLER, OF NEW YORK, N. Y.

SAFETY DEVICE FOR AEROPLANES

Application filed May 7, 1929. Serial No. 361,200.

This invention relates to safety devices for aeroplanes and more particularly to a novel and improved means for maintaining an aeroplane body afloat when necessity requires 5 that said aeroplane land on a body of water.

One of the objects of my invention is to provide in the fuselage of an aeroplane, an inflatable captive envelope or balloon, capable of being released and inflated to provide 10 sufficient buoyancy and prevent the aeroplane from sinking.

More specifically my invention relates to aeroplane bodies in which the fuselage is provided with one or more compartments 15 preferably in the top and bottom, rearwardly of the main wings including provision for releasing and inflating a captive balloon or envelope having sufficient buoyancy to sustain the aeroplane when it becomes necessary to 20 make a landing on a body of water.

To enable others skilled in the art to more fully comprehend the underlying features of my invention, reference is had to the accompanying drawing forming a part of the 25 specification in which

Fig. 1 is a side view of a conventional type of aeroplane in which my invention is embodied.

Fig. 2 is a side view showing both the top 25 and bottom envelope or balloon released and inflated.

Fig. 3 is a front view.

Fig. 4 is a partial sectional view showing the envelope or balloon compartment.

Fig. 5 is a view similar to Fig. 4 showing the doors or closures when open and connected to the envelope or balloon.

Fig. 6 is a vertical sectional view through the fuselage body showing the compartments and deflated envelope or balloon.

Referring now to the drawings wherein like reference numerals designate corresponding parts throughout the several views, 5 45 designates the body or fuselage of a conventional type of aeroplane, 6, 7 the top and bottom wings respectively connected by struts 8, the rear steering rudder being indicated by numeral 9 and the propeller by 50 numeral 10. While I have shown an aero-

plane having top and bottom wings, it will also be understood that my invention is equally applicable to a monoplane as will be further pointed out.

Rearwardly of the cockpit and wings, the 65 fuselage is provided with a top and bottom envelope or balloon compartment 11, 12 of considerable length formed by lateral partitions 13, 14 which are joined to the sides 15, 16 of the fuselage rendering said compartments practically water-tight to prevent the entry of water to the body proper of the aeroplane. The top compartment is equipped with doors or closures 17, 18 shaped to conform with the contour or curved top of the 65 fuselage, said doors being hingedly connected as at 19, so as to be opened outwardly in the manner shown by Fig. 5. The bottom compartment is equipped with similar doors or closures 20, 21 hinged as at 22 and also adapted to be opened outwardly.

Within the respective top and bottom compartments, I provide a water-proof, envelope, balloon or bag 23, 24 capable of being folded in a substantially flat condition so as to 75 lie within the shallow compartments but releasable therefrom through the doors or closures when opened. Each envelope, balloon or bag is provided with an air valve 25 that may be connected to a motor driven pump or compressor as shown in dotted lines by Fig. 1. This construction is such that either or both envelopes may be inflated depending on conditions, the air capacity of the lower of 80 said envelopes being such as to sustain the 85 aeroplane and its load. However, for safety purposes two envelopes are provided to sustain an excessive load of fuel, equipment and merchandise during transportation. It will be noted that while each envelope or balloon 90 is folded in a comparatively shallow compartment, when said envelope is released and inflated, it is of sufficient size and spread to extend forwardly or above and beneath the 95 cockpit and wings of the aeroplane. The size, shape and spread of the envelope or balloon may be varied in accordance with the type of aeroplane but in any event its buoyancy power must be sufficient to not only 100

maintain the aeroplane afloat but also keep it properly balanced when in the water.

- As shown in detail by Fig. 5, the balloon or envelope is fastened by rings 26 secured within the respective compartments so that in one sense, when the envelope or balloon is inflated, it is more or less stationary. In its folded condition, the envelope or balloon is held within the respective compartments by draw strings 27 which are crossed and passed through the rings, the ends of the strings passing through an eyelet 28 in an end wall 29 and fastened to a ring 30. By cutting or detaching the ends of the draw string, the envelope or balloon is free to be inflated so as to extend outside the doors or closures when opened. The doors or closures are also connected by cables or strings 31 passing through eyelets 32, the ends of the cables or strings being similarly connected to a ring 33. By cutting or releasing the cables or strings connecting the doors or closures, they may be opened to release the balloon or envelope for the obvious purpose. Additional rings 34 and connecting cables or strings 35 are provided to connect both of the envelopes or balloons when in their inflated condition, but such connection can only be made after the envelopes are released.
- Under normal conditions, it will be understood that the envelope, balloon or inflatable members are in their folded concealed position within the compartments the doors being closed. When it becomes necessary to make a forced landing on the water, the bottom doors or closures may be first opened and the lower envelope or balloon inflated. This may take place either before or after the machine alights. If an exceptional load is being carried both envelopes or balloons may be inflated in the above manner or by means of any other suitable apparatus.

While I have shown and described this invention with some degree of particularity, it will be realized that other modifications and changes may be resorted to under special conditions. I therefore do not wish to be limited and restricted to the exact details shown and described but reserve the right to make such changes and modifications as may fairly fall within the scope of the subject matter now being claimed.

Having shown and described my invention, what I claim as new and desire to secure by Letters Patent is:—

1. In a safety equipment for aeroplanes wherein the fuselage is constructed with a shallow top and bottom compartment, an inflatable captive envelope or balloon positioned in collapsed, folded condition within each of said compartments, hinged doors or closures for each of said compartments, said doors being adapted to swing outwardly flatly onto the fuselage whereby either the top or bottom or both envelopes or balloons

may be released laterally to extend directly above and below said fuselage.

2. In a safety equipment for aeroplanes wherein the fuselage is constructed with a shallow top and bottom compartment, an inflatable captive envelope or balloon positioned in collapsed, folded condition and attached to the walls of said compartments, hinged doors or closures adapted to swing outwardly beyond the sides of the fuselage and means for releasing said doors, each of said envelopes or balloons being of sufficient spread to extend laterally of the fuselage and below and over the main wings of said aeroplane.

3. In a safety equipment for aeroplanes, compartments in the fuselage opening upwardly and downwardly therefrom, and inflatable envelopes or balloons adapted to be collapsed into said compartments and means for inflating said envelopes or balloons so that they emerge from said compartments, said envelopes or balloons spreading flatly and horizontally, directly below and above the aeroplane, and substantially covering the fuselage and wings thereof.

In testimony whereof I affix my signature.

PIROSKA ELLER.
